(57) **CLAIM**

The ornamental design for a shoe, as shown and described.

DESCRIPTION

FIG. 1 is a first side view of a shoe showing my design;

FIG. 2 is a second side view thereof;

FIG. 3 is a rear view thereof;

FIG. 4 is a first side rear perspective view thereof; and,

FIG. 5 is a second side rear perspective view thereof.

The even-length broken lines are directed to environment, represent unclaimed subject matter, and form no part of the claimed design. The oblique line shading depicts a surface that is transparent, translucent, highly polished, or reflective.
